HOLDER FOR WRITING IMPLEMENTS

Fred Lowenthal, Brooklyn, N. Y.

Application November 8, 1954, Serial No. 32,993

Term of patent 14 years

(Cl. D74—21)

Fig.1.

Fig.2.

Fig.3.

To all whom it may concern:

Be it known that I, Fred Lowenthal, a citizen of the United States, residing in Brooklyn, county of Kings, and State of New York, have invented a new, original, and ornamental Design for a Holder for Writing Implements, of which the following is a specification, reference being had to the accompanying drawing, forming a part hereof in which:

Fig. 1 is a front elevational view of a holder for writing implements, embodying my new design;

Fig. 2 is a rear elevational view of the same;

Fig. 3 is a top plan view of the same, and

Fig. 4 is an end view of the same.

I claim:

The ornamental design for a holder for writing implements, as shown.
